(57) **CLAIM**

The ornamental design for a decorative lever, as shown and described.

DESCRIPTION

FIG. 1 is a front, right-side perspective view of the decorative lever.

FIG. 2 is a front view thereof.

FIG. 3 is a top view thereof.

FIG. 4 is a right-side view thereof.

FIG. 5 is a left-side view thereof.

FIG. 6 is a bottom view thereof; and,

FIG. 7 is a rear view thereof.

The broken lines are for the purpose of showing illustrative attachment shanks for the decorative lever, and they form no part of the claimed design.
